(57) **CLAIM**

The ornamental design for a spoke segment for a vehicle wheel, as shown and described.

DESCRIPTION

FIG. 1 is a top, front perspective view of a spoke segment showing my new design;

FIG. 2 is a front elevational view thereof;

FIG. 3 is a rear elevational view thereof; and,

FIG. 4 is a side elevational view thereof.

The broken line representations of items in FIGS. 1-4 are for purposes of illustration only, and form no part of the claimed design.

1 Claim, 4 Drawing Sheets

FIG. 1

FIG. 2

FIG. 3

FIG. 4
